UNITED STATES PATENT OFFICE.

SIMON W. BENSON, OF CHICAGO, ILLINOIS.

SUPPORTER FOR BOOKS, TELEPHONES, AND THE LIKE.

No. 895,536.

Specification of Letters Patent. Patented Aug. 11, 1908.

Application filed October 26, 1905. Serial No. 284,437.

To all whom it may concern:

Be it known that I, SIMON W. BENSON, a citizen of the United States, residing at Chicago, county of Cook, and State of Illinois, have invented a certain new and useful Improvement in Supporters for Books, Telephones, and the Like, of which the following is a description.

My invention relates to that class of devices employed for holding a book, copy holder, telephone, or other article, in position where it may be out of the way when not in use but readily and conveniently accessible and in the most desirable position when required for use.

The object of my invention is to produce a strong, durable, and convenient device of the kind described with the parts so formed and arranged as to require the minimum amount of adjustment or care.

To this end my improvement consists in the novel construction, arrangement, and combination of parts, herein shown and described and more particularly pointed out in the claims.

In the accompanying drawings wherein like or similar reference characters indicate like or corresponding parts; Figure 1 is an elevation of an adjustable form of my device attached to the end of a desk and supporting a telephone and a book. Fig. 2 is a section taken substantially on line 2—2 of Fig. 3. Fig. 3 is an end elevation of a clamp and associated parts for engaging a book. Fig. 4 is a slightly modified form of my device. Fig. 5 is a detail of a telescoping rod which may be employed in my device. Fig. 6 is an enlarged end elevation of the book clamp showing the parts in position when the book is open. Figs. 7 and 8 are enlarged details showing modified forms of construction. Figs. 9 and 10 are enlarged details of the adjustable arm clamp preferably employed. Fig. 11 is an elevation of a non-adjustable book holder as applied to a wall with the book not in use. Fig. 12 is a view similar to Fig. 11 but showing the book open as in use. Fig. 13 is a section taken substantially on line 13—13 of Fig. 11. Fig. 14 is a detail showing a modified form of swivel.

In the form of my device shown in the drawings, an upright 1 is rotatably supported by a bracket 2 which may be attached to any suitable object as a desk, table, partition or wall. Any desired number

of arms 3—4 for directly supporting various objects may be attached to the upright 1 in any desired manner.

As shown in Fig. 1 the arm 3 is provided with a book holder and is attached to the upright 1 by means of a friction joint 5 which permits the arm 3 to be adjusted vertically to any desired angle or inclination. The joint 5 is also freely rotatable and vertically adjustable upon the upright 1.

The book holder may be of any suitable form or construction, as shown a spring clamp 6 is provided to grasp the back of the book and is preferably of sufficient length to extend slightly beyond the covers of the book at each end to protect the same. This clamp may be formed of a single piece of suitably formed material as shown in Fig. 7, with any desired number of swivels 8 provided with screws 10—10 for drawing the jaws of the clamp together to engage the book or other object to be supported; or as shown in Figs. 6 and 8, the clamp 6 may be formed of suitably shaped bars 13, 13' and one or more springs or flexible members 14 arranged to connect these bars with the swivels 8 and screws 10 as before described.

The swivels 8 are preferably positioned near each end of the clamp 6 and are attached thereto by means of the screws 10 which may be arranged to engage the swivel 8 in any suitable manner. As shown in Fig. 6 a single threaded opening is provided for receiving the screws 10 while in Figs. 7 and 14 this portion of the swivel is shortened and a separate threaded opening is provided for each screw obviously the latter form provides the greatest range of adjustment but either form may be employed with satisfactory results. A tubular sleeve 11 is also provided upon each swivel for rotatably engaging the arm 3 and thus attaching the clamp 6 to the arm.

Means are preferably provided to prevent longitudinal movement of the swivels 8 upon the arm 3 except when the clamp 6 is in its upright position, that is face upward as shown in Fig. 6. One of the sleeves 11 is preferably so formed that when in this position a slight longitudinal movement of the clamp 6 will lock the same against rotation upon the arm.

Any desired means may be employed to control the longitudinal position and also to lock the clamp 6 against rotation upon the

arm 3. As shown a collar 12 is provided upon the arm at one end of one of the sleeves 11 and a pin 14 is provided at the opposite end of the other sleeve. A suitable slot 15 is provided in the end of the sleeve adjacent the pin so positioned that when the clamp 6 is in the desired position the pin 14 is in position to enter the slot and by a slight longitudinal movement the parts are thus positively engaged.

In the form shown, covers 16—16 corresponding in size to the object supported are hinged to each side of the clamp 6 by means of a plurality of stirrups 40 each loosely mounted upon a screw 10 and a loop 41 for each stirrup co-operating therewith and securely attached to the covers 16, the parts being so formed that when the holder is in use a part of each of the loops 41 will rest upon the head of a screw 10 to support the loops in an extended position so that the covers 16 will lie out flat as shown in Fig. 6 to support the book in convenient form for use but when the holder is inverted the covers will hang down on each side as in Figs. 1 and 11 and thus protect the object between them.

If desired clasps or equivalent means 17 may be provided upon the covers to hold the same together and thus add to the security of the object between them, and if preferred a book may be thus held in place in the holder without engaging the same between the jaws of the clamp at all.

The joint 5 may be of any desired form or construction. As shown two concave plates 18 and 19 are provided with means for attachment to the upright 1 and arm 3 respectively. A disk of friction material 20 is shown positioned between the adjacent faces of the plates and a bolt 21 having a suitable nut 24 is provided to serve as an axis for the plates and to control the pressure between them. In the form shown the plate 18 is revolutely attached to the upright 1 by the bolt 21 the head 22 of which is of tubular form arranged to loosely fit upon the upright 1 and is rigidly attached to the plate 18. The plate 19 is preferably provided with a cylindrical portion 23 having openings provided on each side to receive the arm 3 and hold the same substantially parallel to the face of the plate, the bolt 21 extending through an opening in the arm to prevent turning or longitudinal movement in the openings.

To prevent a possible alteration in the adjustment of the nut 24 by the movements of the plate 19 and also to increase the frictional resistance of the joint, a washer 25 is provided between the nut 24 and plate 19 the washer 25 being so arranged that it can not be rotated upon the bolt 21. Any suitable means may be employed for this purpose. As shown the washer 25 is extended 65 and formed so as to engage the upright 1 for

this purpose. The vertical position of the joint 5 upon the upright is controlled by a collar 26 provided with a set-screw 27 or other well known means to control its position.

In the form shown a stop or lock is provided to limit the inclination of the arm 3. This stop consists of a part 31 upon the plate 18 arranged to engage a projection or similar part 32 upon the plate 19 and thus prevent a further relative movement between the plates and associated parts.

The arm 4 in Fig. 1 is shown telescoping to give a wider range of movement to the article supported which in this case is shown 80 as a telephone pivotally attached to the extremity of the arm by means of a band 28 so that at any inclination of the arm 4 the telephone will remain in a vertical position.

A friction joint 29 is also provided, similar 85 in construction to the joint 5 except that it is shown rigidly mounted upon the upright 1 the concave plate being preferably attached to the upright 1 in this form in the same manner that the concave plate 19 was attached 90 to the arm 3 shown in Fig. 10. The arm 4 is extended beyond the joint and provided with a counterbalance spring 30 to facilitate the operation of the joint especially where the object supported is quite heavy or the arm 95 supporting the same of considerable length. In this form also two stops or locks are shown arranged to limit the movement of the arm 4 in both directions the locks being preferably formed the same as the one upon the joint 5 100 and heretofore described. The arm 4 may be arranged to telescope in any preferred manner. In Fig. 5 a form is shown in which the inner member is provided with a fixed sleeve or collar 33 at its end and the outer or 105 tubular member is split at its end and provided with a clamp 34 having a set-screw 35 or other means to press against one side of the tubular outer member and force the same inward so that it is impossible to carelessly separate the two members of the arm. If desired also the set-screw 35 may be tightened sufficiently to clamp the two parts together at any point desired and thus prevent 110 any movement between them.

If desired any suitable means may be provided to prevent rotation between the two portions of the arm 4. As shown a pin or equivalent means 36 is provided upon the collar 33 and a groove 37 is formed upon the 120 interior of the tubular part of the arm to engage the pin 36 for this purpose. Obviously when so arranged if desired the book or paper holder shown attached to the arm 3 may be mounted upon the tubular part of the 125 arm 4 and operate in every respect the same as heretofore described.

In Fig. 4 the arm 3' is shown provided with a plain sleeve 38 for engaging the upright, this form while permitting the arm to 130

be rotated about the upright and adjusted vertically by means of the collar 26 is obviously an inferior equivalent for the form shown in Fig. 1 as the inclination of the arm 5 3' is fixed and can not be adjusted.

In the form shown in Figs. 11 and 12 the upright and the arm supporting the book holder are formed of a single piece and can therefore have no adjustment. It is however a cheap and convenient form for mounting directories or other books which are only consulted momentarily and where the accurate adjustment of the book is of comparatively small importance.

15 In Figs. 1, 2, 6, 11, and 13 the swivels 8 are shown so proportioned that the arm is positioned at a considerable angle to the clamp 6. The object of this arrangement being to hold the book or other paper when not in use as 20 nearly level as possible, and when the holder is turned to bring the book in position for use, to secure as great an inclination as possible without altering the adjustment of the arm supporting the book.

25 By the term "upright" as referring to the book or paper holder or clamp I desire to be understood as meaning the position of the holder as shown in Figs. 6 and 12 in which the holder is so positioned that a book or papers supported therein may be opened and 30 conveniently examined with their leaves extended.

Obviously various immaterial modifications may be made in my improvement without departing from the spirit of my invention, hence I do not wish to be understood as limiting myself to the exact form and construction shown.

What I claim as new, and desire to secure 40 by Letters Patent is:—

1. In a device of the kind described, an arm, a holder loosely and rotatably mounted upon said arm, and means for automatically locking said holder to said arm to prevent its 45 rotation when the holder is in its upright position.

2. In a device of the kind described, a rotatable arm, a holder loosely and rotatably mounted upon and positioned at an angle to 50 said arm, and means operable only when said holder is in its upright position for locking said holder to said arm to prevent its rotation.

3. In a device of the kind described, an 55 arm, and a holder comprising a clamp, a plurality of swivels rotatably mounted upon said arm, and adjustable means for attaching said swivels to said clamp and for controlling the distance between the jaws of 60 said clamp.

4. In a device of the kind described, an arm, a plurality of swivels rotatably mounted upon said arm, a clamp inclosing said 65 swivels, means for controlling the distance between the jaws of said clamp for at-

taching the clamp to said swivels, and means for locking said clamp against rotation when in its upright position.

5. In a device of the kind described, an arm, a plurality of swivels rotatably mounted upon said arm, a spring clamp inclosing said swivels, and screws engaging said swivels arranged to control the distance between the jaws of said clamp and attaching the clamp to said swivels. 75

6. In a device of the kind described, an arm, a plurality of swivels rotatably mounted upon said arm, a spring clamp inclosing said swivels and positioned at an angle to said arm, and means attached to said swivels 80 for controlling the distance between the jaws of said clamp and for attaching the clamp to said swivels.

7. In a device of the kind described, a stationary upright, a non-rotatable arm supported by said upright, a holder mounted upon and rotatable about said arm, and means for automatically locking said holder against rotation only when in its upright position. 85

8. In a device of the kind described, a book holder provided with a clamp for rigidly engaging a book to support the same in any position, and covers pivotally attached to each side of said clamp, in combination 90 with an arm extending longitudinally of said clamp, means for mounting said clamp upon said arm and locking mechanism to prevent movement between said clamp and arm. 95

9. In a device of the kind described, a book holder provided with a clamp for rigidly engaging a book to support the same in any position, and covers pivotally attached to each side of said clamp, in combination 100 with an arm extending longitudinally of said clamp, means for rotatably mounting said clamp upon said arm, means for supporting said arm, and locking mechanism adapted to prevent rotation between said clamp and arm. 105

10. In a device of the kind described, a nonrotatable upright, an arm, a friction joint for connecting said arm and upright and controlling the inclination of said arm, said joint being rigidly attached to said arm and rotatably and adjustably attached to said upright, and a holder mounted upon said arm. 110

11. In a device of the kind described, an upright and an arm, in combination with a friction joint connecting said arm and upright 115 and controlling the inclination of said arm, means for adjusting the resistance between the parts of said joint and a positive stop upon said joint to limit vertical movement of the free end of the arm.

12. In a device of the kind described, an upright and an arm, in combination with a friction joint controlling the inclination of the arm and connecting said arm and upright, said joint consisting of two plates, a 120

4
disk of friction material positioned between said plates, means for controlling the pressure between said plates, and means for attaching said plates to said arm and upright respectively.

13. In a device of the kind described, a book holder provided with a clamp for rigidly engaging a book to support the same in any position, covers pivotally attached to each side of said clamp, and means for supporting said covers in an extended position when said clamp is in an upright position, in combination with an arm extending longitudinally of said clamp and rotatably connected therewith means for supporting said arm, and locking mechanism to prevent rotation between said clamp and arm.

14. In a device of the kind described, a friction joint consisting of two concave plates, a disk of friction material positioned between said plates, an axis common to said plates provided with means for adjusting the pressure between the same, a projection formed upon each plate arranged to cooperate to limit the rotary movement between the plates, and means for attaching each plate in position.

15. In a device of the kind described, an

arm, a plurality of swivels rotatably mounted upon said arm, a spring clamp inclosing 30 said swivels, means for controlling the distance between the jaws of said clamp and attaching the same to said swivels, and means, consisting of a pin projecting from said arm and a slot formed in one of said swivels 35 adapted to coöperate with said pin, for locking said clamp against rotation upon said arm.

16. In a device of the kind described, a holder comprising a clamp, screws for controlling the position of the jaws of said clamp, and a stirrup attached to each screw, in combination with two covers, each provided with loops for engaging said stirrups to pivotally support said covers, the parts being so 45 formed that said loops will rest upon said screw heads to support said covers in an extended position when said holder is in its upright position.

In testimony whereof, I have hereunto 50 signed my name in the presence of two subscribing witnesses.

SIMON W. BENSON.
